METHOD OF IMPRESSING DESIGNS UPON
PILE FABRICSWilliam R. Todd, Shelton, Conn., assignor to The
Sponge Rubber Products Company, Shelton,
Conn., a corporation of Connecticut

Application August 16, 1938, Serial No. 225,251

4 Claims. (Cl. 154—2)

This invention relates to fabrics bearing designs either in relief or impressed into the substance of the fabric and also relates to improved methods for producing fabrics carrying such designs. Particularly the invention relates to designs of this nature produced in pile fabrics and to fabrics whose bodies are warped to produce the design and backed by a layer of sponge rubber for making the design permanent and for other purposes.

In textile fabrics possessing a pile or nap a design may be produced by bedding down the naturally upstanding fibers of the pile or nap. It has been proposed to hold the depressed pile fibers firmly down against the woven body of the fabric by impregnating it with glue or gum to make the design permanent. In part, this has been considered necessary because the body of the fabric has remained flat and undistorted so that restoration of the pile or nap to its original upstanding condition would impair or obliterate the design.

An object of these improvements is to impart to a fabric, and preferably to a textile fabric whether or not possessed of nap or pile, and in such manner that the fabric retains a cloth-like flexibility, a permanent decorative design delineated partially by relatively raised and relatively depressed portions of the flexible body of the fabric, and partially, if the fabric possesses a pile or nap, by the contrast in light-reflecting characteristics of an upstanding and a bedded down pile or nap.

A further object is to render the decorative design absolutely permanent and proof against obliteration by bonding against the back, or pileless surface, of the fabric a continuous sheet-like layer of sponge rubber whose face which contacts with the surface of the fabric conforms to a warped contour of the body of the fabric so that the sponge rubber underlies and covers both the relatively raised portions and the relatively depressed portions of the fabric. These raised portions may comprise a panel-like area surrounded by the depressed portions or the depressed portions may comprise a panel-like area surrounded by the raised portions.

A further object of the invention is to warp or distort the body of the fabric by means of the force exerted by an expanding plastic, as for instance, sponge rubber compound when the latter is "blown" and then vulcanized in bonded contact with the back, or pileless surface, of the fabric while both fabric and compound are im-

prisoned within a confined space bounded by molding surfaces.

A further object is to determine selectively and at will the configuration of the decorative design to be imparted to the fabric by making use of a loose or removable template, stencil or other pattern-like device interposed between the free or pile carrying face of the fabric and the mold surface which borders upon the confined space. 10 This, it has been discovered, comprises a means for effectively depressing or bedding down pile or nap in those surface areas of the fabric which are contacted by the template or stencil device so that there results a marked contrast in appearance between the pile surface which is so bedded down and the pile surface which is not. The contrast in luster of the fibers so produced emphasizes the design beyond the mere effect of warping the body of the fabric, itself.

20 A still further object is to increase this contrast in the degree of luster exhibited respectively by the upstanding and bedded down pile by a novel process of depressing the pile by means of the pressure exerted thereupon by an expanding plastic while the fabric and the template or stencil device and the plastic are being conveyed together between two traveling belts through a zone of sufficient heat to cause the plastic, such as sponge rubber compound, to "blow" and expand and then to vulcanize into permanently set sponge rubber securely bonded to the back surface of the fabric. It is found that this process serves to so bed down the pile or nap of the fabric that the fibers thereof tend to be aligned in a more common direction. This increases their light-reflecting ability and produces more luster than is exhibited by fibers bedded down in diverse directions of alignment.

30 35 40 45 A further purpose of the invention is the provision of fabrics of novel appearance having decorative designs impressed thereupon and permanently maintained therein by my improved processing steps, examples of which are explained in the following description in which reference is had to the accompanying drawing wherein:

Fig. 1 is a perspective view of the pile carrying face of a textile fabric carrying decorative designs imparted thereto by the improved methods herein disclosed.

Fig. 2 is an enlarged view taken in section on the plane 2—2 in Fig. 1.

Fig. 3 is a similar view taken in section on the plane 3—3 in Fig. 1.

Fig. 4 is a detail perspective view of a template-

like pattern device used to produce the design near the right end of the fabric in Fig. 1.

Fig. 5 is a detail perspective view of a stencil-like pattern device used to produce the design near the left end of the fabric in Fig. 1.

Fig. 6 is a view taken in vertical cross section lengthwise through the fabric strip of Fig. 1 while the latter, together with the template of Fig. 4, and the stencil of Fig. 5, is being conveyed by and between endless belts through a zone of vulcanizing heat in any suitable processing machine, the sponge rubber compound being shown as it appears before the heat causes it to blow and expand.

Fig. 7 is a view similar to Fig. 6 showing the effect upon the body of the fabric, and upon the pile carried by its upper surface, of the heat applied to the sponge rubber compound as it travels, such compound here being shown as having become vulcanized into permanently set sponge rubber bonded to the warped body of the fabric.

While any fabric having a suitable pile or nap or even a fabric without pile or nap may be subjected to the treatment contemplated by this invention for imparting a design thereto, I prefer to employ any of the commonly known textile fabrics or cloths possessing a nap formed by fibers of the body threads brushed up for this purpose by well known processes, or formed by loops of pile fibers whose uncut ends are wedged within the interstices of the woven body of the fabric. The latter type of fibers comprising a pile is illustrated in Figs. 2 and 3.

Such fabrics may be taken in the condition they are found in the market and provided on the back, or pileless surface, thereof with a thin layer of sponge rubber compound or other suitable plastic in a manner evenly and completely to cover such surface of the fabric.

In Fig. 6 such facing of sponge rubber compound appears at 10, above and in contact with which, is the body 11 of the fabric whose opposite face carries the uniformly and freely upstanding pile 12. The flat surfaced template-like pattern device 13 of Fig. 4 is shown resting freely and without pressure upon the top of the pile surface of the fabric as is also the flat surfaced stencil-like pattern device 14 of Fig. 5. All of these parts in Fig. 6 are sandwiched between a lower flexible conveyor belt 15 and an upper like conveyor belt 16. Both of belts 15 and 16, of which only a short stretch is shown in Fig. 6, may in their entirety be endless belts traveling from left to right at preferably the same linear speed, and carrying with and between them, all of the said working materials for imparting to the fabric the design of these improvements. The lower belt may be supported, and slide in flat surfaced contact with, the lower hot plates 17 above which the upper hot plates 18 are sufficiently spaced to initially cause no squeezing of any of the material carried between the conveyor belts.

As the belts and the materials conveyed between them progress substantially in unison past successive hot plates, the heat delivered by the latter through the material of the belts to the space therebetween causes the sponge rubber compound 10 to blow and expand and hence to press the body of the fabric, together with the pile carrying face thereof, forcibly upward. As the ability of the upper belt 16 to rise as it travels past the hot plates is positively limited by the lower surface of the upper hot plates 17, portions of the fabric body with its pile face are pressed or squeezed against the bottom surface of tem-

plate 13 and stencil 14 while other portions of the fabric body with its pile face are forced upwardly past the plane of the lower surfaces of the template and stencil and into the vacant spaces or hollows adjacent thereto. These vacant spaces or hollows are indicated in Fig. 6 at 19. In Figs. 2 and 7, after the expansion and vulcanization of the compound into the sheet-like body 22 of sponge rubber having an upper impaneled face, spaces 19 are seen to be occupied but incompletely filled by the embossed body or carcass of the fabric and the expanded rubber 22.

For reasons which will be apparent, the fibers of the pile which are encountered by the lower surface of the template 13 and stencil 14 are subjected to materially greater pressure as they are squeezed against said surface by the uplift of the expanding sponge rubber compound than are the fibers of the pile which are lifted into the vacant spaces 19 toward the surface of belt 16. While the intensity of the pressures against different areas of the pile face may be determined by relationships between the thickness of the template or stencil, the weight of the woven body of the fabric, the upstanding length of the pile fibers, the thickness and "blowing" ingredients of the sponge rubber compound, and the space available to these materials between the bottom hot plates 17 and top hot plates 18, in general such relationships may be chosen as will impart flat surfaces to the raised areas of the fabric in hollows 19 without producing enough pressure thereof against the top conveyor belt 16 to squeeze the pile thereagainst sufficiently to permanently depress it or bed it down. The resulting product is illustrated in Figs. 1, 2 and 3, wherein the pile fibers which are left freely upstanding appear at 12, while the pile fibers which have been bedded down against the body 11 of the fabric are indicated at 12'.

Referring particularly to Figs. 2 and 3, the two sets of pile fibers represented in broken lines as upstanding from the depressed area of the body of the fabric illustrate how permanency of the impressed design is achieved even though the pile or nap which has been bedded down should become lifted again. In these figures it is apparent that the design would still be delineated by the presence of a lower exposed surface of the pile opposite the depressed areas of the body of the fabric.

Figs. 2 and 3 further illustrate the laying or bedding down of the pile fibers in a common direction of alignment generally lengthwise in the direction of travel of the conveyor belts 15 and 16. It is assumed that this bedding down of the fibers in a common direction of alignment results from the travel of the materials between the conveyor belts while the sponge rubber compound expands and exerts its pressure against the body of the fabric. A superior ability of the bedded down fibers to reflect light results and enhances the contrast in appearance between the design and its background.

These improvements, however, are not confined to performing the plastic heating step of the process while the latter involves travel of the materials being treated. The heavy broken lines in Figs. 2 and 3 represent sections of an upper stationed mold 20 and a lower stationed mold 21 which may be separable in any well known way to admit the materials to be processed and then fixedly stationed in their relationship as shown and heated in any well known way to cause the "blowing" expansion and vulcanization of the sponge rubber compound or other plastic with-

out travel being involved. Fig. 2 illustrates a recess sunk in the face of mold section 20 to accommodate the raised area of the design bearing fabric while Fig. 3 illustrates a boss protruding from the face of mold section 20 to form the depressed area of the design bearing fabric.

Regarding the materials employed in a preferred embodiment and practicing of the invention as herein shown, the conveyor belts 15 and 16 may be of canvas suitably surfaced if desired to produce a smooth face for contact with the work, and the template 13 and stencil 14 may be made of fibre or of fabric impregnated with suitable hardening substances, but in any case should be impervious to warping or deterioration from the effects of a temperature sufficient to vulcanize rubber.

The sponge rubber compound proposed may be replaced with pre-molded sheets of ordinary or solid rubber bearing impaneled surfaces having design shaped recesses registering with overlying projections or template shapes in the upper mold section and thus be bonded to the body of the fabric in a manner to warp the same into conformity with the pattern by the use of some adhesive. The fibers of the pile would be correspondingly embedded or glued down by the pressure between the mold sections employed to squeeze the body of the fabric into distorted conformity with the impaneled upper surface of the pre-molded rubber sheet, and a designed fabric will result whose flexibility depends upon the softness and the thinness of the rubber employed. Here, as in the case of the use of sponge rubber, the impressed design is maintained permanently in the body of the fabric by the cling of the impaneled surface of the rubber sheet thereto.

In the application of a sheet of sponge rubber compound to the back of the fabric, a continuous length of the fabric together with a continuous length of the compound may be played off from respectively separate supply rolls and passed in face-to-face contact through suitable rolls for causing the fabric and the compound to adhere. When the assembled fabric and compound strip is then fed into a vulcanizing machine between the conveyor belts 15 and 16, designs of any character may be imparted successively along its traveling length by the freedom to choose different template and stencil devices for insertion between the top conveyor belt and the pile surface of the fabric as the fabric continuously enters the machine. As the vulcanized product leaves the machine this continuous fabric strip with its rubber backing may be cut into suitable lengths bearing the same or different designs and thus a large daily output of selectively designed product is possible by this novel and continuous process of imparting designs to the physical substance of a pile fabric.

Many modifications of the product and steps in the process herein described to illustrate the invention will occur to those skilled in the art, as for instance backing the body of the fabric with a facing of rubber or sponge rubber which possesses the same thickness in the depressed areas of the body of the fabric as in the raised areas, it being seen that this can be accomplished by the use of a suitable impaneled mold section underneath as well as on top of the materials to be processed. Hence the appended claims are intended to cover all variations of and substitutes for the particular materials, forms and functions herein described that are fairly embraced within their terms.

I claim:

1. In a process for shallow impaneling a permanent design in both the pile and carcass of a limp woven pile carrying fabric, the steps which comprise, disposing adjacent areal portions of the pile carrying face of said fabric carcass toward and in areal register with adjacent flat pattern forming support surfaces located respectively in relatively offset parallel planes, blowing sponge rubber compound to cause it to expand while in contact with said fabric carcass in all of its said areal portions while confining said expanding compound and carcass and pile in a manner to cause said compound to press the carcass and pile of said fabric simultaneously toward all of said adjacent offset flat support surfaces with an areally distributed force sufficient to emboss and offset the entire thickness of said carcass in certain of said areal portions from its original normal alignment with the entire thickness of said carcass in others of said areal portions, and so predetermining the volume expandability and degree of confinement of said compound in relation to the extent of offset of said pattern forming support surfaces that the said pile is squeezed against only the nearest of said surfaces with sufficient force to bed down said pile.

2. The method of imparting a permanent design to a flexible woven fabric having a pilous face consisting of initially upstanding pile fibers, which consists in, flanking said pilous face of the fabric by means of adjoining relieved and depressed mold surfaces, confining in surface contact with the back of said fabric a continuous sheet-like body of uncured sponge rubber compound with the aid of a mold wall fixedly spaced from said mold surfaces, so proportioning the thickness of said compound and its capacity to expand responsive to heat in relation to the space between said mold surfaces and said mold wall that the maximum expansion of said compound is capable of pressing certain areal portions of the pilous face of said fabric against said relieved mold surfaces with sufficient force permanently to bed down the pile fibers in said certain portions but is incapable of pressing other areal portions of said pilous face against said depressed surfaces with sufficient force permanently to bed down pile fibers in said other areal portions, and heating said sponge rubber compound sufficiently first to cause the said expansion and then to vulcanize the compound into adhering contact with the back of the fabric.

3. The method of imparting a permanently bedded down deformation to initially free and upstanding pile fibers of a flexible pile fabric for affecting the luster of said pile over patterned partial areas of the pilous face of said fabric and without admixture of extraneous substance to the pile thereof, which consists in, presenting to said initially upstanding pile fibers in said partial areas pressure resistive mold surfaces relieved to delineate a pattern and flanked by adjoining hollows, simultaneously subjecting the back of said fabric opposite the said resistive surfaces and also opposite the said hollows to the pressure of a continuous body of heated expanding sponge rubber compound in a manner to emboss the fabric somewhat into said hollows and to squeeze the pile fibers in only said partial areas against said relieved resistive surfaces with sufficient force and in the presence of sufficient heat to impart to said squeezed fibers a

permanently bedded-down deformation, so pre-relating the volume and expansive properties of said compound to the depth of said hollows that the maximum expansion of said compound forces said pile into said hollows insufficiently far to cause the fibers of said pile to become bedded down therewithin, and vulcanizing said compound into adhering contact with said fabric thereby to maintain the embossed shape of the latter.

4. The method of impaneling designs in the carcass of a woven fabric having a pilous face without intermixing extraneous substance with the pile fibers of said face, which consists in presenting to initially upstanding pile fibers in partial areas of said pilous face pressure resistive mold surfaces relieved to delineate a pattern and flanked edgewise by adjoining hollows, simultaneously subjecting the back of the carcass of said fabric opposite the said resistive surfaces

and also opposite the said hollows to the pressure of a continuous body of heated expanding sponge rubber compound in a manner to squeeze the pile fibers in only said partial areas against said relieved resistive surfaces with sufficient force and in the presence of sufficient heat to impart to said squeezed fibers a permanently bedded-down deformation, so pre-relating the volume and expansive properties of said compound to the depth of said hollows that the maximum expansion of said compound forces the pile and carcass of said fabric sufficiently far into said hollows to produce panel-like relative offsetting of adjoining flat faced sections of said fabric carcass but insufficiently far to cause the fibers of said pile to be bedded down within said hollows, and vulcanizing said compound into adhering contact with said fabric thereby to maintain said offsetting of said fabric sections.

WILLIAM R. TODD.
